UNITED STATES PATENT OFFICE.

SAMUEL E. CARLIN, OF CHICAGO, ILLINOIS, ASSIGNOR, BY MESNE ASSIGNMENTS, TO
UNDERWOOD COMPUTING MACHINE COMPANY, OF NEW YORK, N. Y., A CORPORA-
TION OF NEW YORK.

CALCULATING-MACHINE.

1,287,218.

Specification of Letters Patent. Patented Dec. 10, 1918.

Application filed November 26, 1910. Serial No. 594,254.

To all whom it may concern:

Be it known that I, SAMUEL E. CARLIN, a citizen of the United States, residing at Chicago, in the county of Cook and State of Illinois, have invented certain new and useful Improvements in Calculating-Machines, of which the following is a specification.

This invention relates to improvements in calculating machines of the type illustrated 10 in my application for United States Letters Patent, Serial No. 547,800, filed March 4, 1910, and in which application there is shown and described an improved calculating attachment for typewriting machines 15 embodying registering mechanism comprising registers or totalizers and traveling actuating means therefor, which actuating means is adapted to be moved or advanced to change its denominational relation to the 20 number bearing wheels or members of the totalizer, this movement being accomplished by the advancing movement of the typewriter carriage.

There is also shown and described in the 25 above referred to application mechanism whereby the typewriter carriage may be automatically returned to its starting position and this return movement of the carriage also served as a means for automatically 30 returning the traveling actuating mechanism of the totalizers.

In the present application there is also provided a similar traveling actuating mechanism which is adapted to be automatically 35 advanced as the typewriter carriage is advanced but it is one of the objects of the present invention to provide an improved calculating machine having means whereby the typewriter carriage and the traveling 40 actuating mechanism may be returned to their normal or starting positions independently with respect to each other.

A further object is to provide improved 45 means for operatively connecting the typewriter carriage with the traveling actuating mechanism of the totalizers, and improved means whereby the connection may be rendered inactive whereby the carriage and the traveling actuating mechanism for the totalizers may be independently returned.

A further object is to provide improved 50 means whereby the typewriter carriage may be automatically returned, at will, to its ini-

tial or starting position from any point to which it has advanced.

A further object is to provide improved stop mechanism for limiting the return movement of the traveling actuating mechanism.

To the attainment of these ends and the 60 accomplishment of other new and useful objects, as will appear, the invention consists substantially in the features of novelty in the construction, combination and arrangement of the several parts hereinafter more 65 fully described and claimed and shown in the accompanying drawings illustrating an embodiment of the invention, and in which—

Figure 1 is a detail top plan view, partly in section of the forward portion of the 70 mechanism, showing a portion of the totalizers and the traveling actuating mechanism therefor.

Fig. 2 is a detail sectional view on line 75 2—2, Fig. 1.

Fig. 3 is a detail top plan view, partly in section and with parts broken away, of the mechanism for advancing the traveling actuating mechanism and the mechanism for automatically returning the typewriter carriage 80 and the traveling actuating mechanism to their initial positions.

Fig. 4 is a side elevation taken on the line 4—4, Fig. 3.

Fig. 5 is a sectional view taken on the line 85 5—5, Fig. 3.

Fig. 6 is a view of the clutch mechanism forming a portion of the connection between the typewriter carriage and the advancing 90 mechanism of the traveling actuating mechanism for the totalizers.

Fig. 7 is a sectional view on line 7—7, Fig. 3.

Fig. 8 is an enlarged detail sectional view 95 on line 8—8, Fig. 3.

Fig. 9 is a detail perspective view of one end of the arm or lever which is connected with the totalizer traveling actuating mechanism for advancing and returning the lat- 100 ter.

Fig. 10 is a detail sectional view on line 10—10, Fig. 3.

Fig. 11 is a detail sectional view on line 11—11, Fig. 10.

Fig. 12 is a perspective view of the oper- 105 ating lever of the clutch mechanism which

controls the return of the traveling actuating mechanism.

Fig. 13 is a detail perspective view of the bracket which supports the lever or link 5 shown in Fig. 12.

Fig. 14 is a sectional view taken on line 14-14, Fig. 16, with parts broken away.

Fig. 15 is a detail view, partly in section and as taken on line 15-15, Fig. 16, of the 10 stop arm and the stop coöperating therewith for limiting the return movement of the traveling actuating mechanism.

Fig. 16 is a detail view on line 16-16, Fig. 3, with parts broken away.

Fig. 17 is an elevation partly in section showing the manner in which the mechanism is connected to the typewriter carriage.

Fig. 18 is a detail view taken on line 18-18, Fig. 3.

Fig. 19 is a sectional view on line 19-19, Fig. 18.

Fig. 20 is a detail perspective view of the stop pawl or arm shown in Fig. 18.

Fig. 21 is a detail section taken from front 25 to rear of the machine, showing the relative arrangement of the computing mechanism to the typewriting mechanism, parts being omitted for the sake of simplifying the showing.

30 Referring more particularly to the separate parts of this invention as embodied in the form shown in the drawings (Fig. 21), 1 indicates numeral keys and 2 character keys, which depress key-levers 3 to rock bell 35 cranks 4 and swing type bars 5 up against the front side of a platen 6 carried by a carriage 42. The carriage 42 is given a step-by-step movement by means of a spring barrel, not shown, under the control of an es-

capement mechanism indicated in general at 7. This escapement mechanism includes a rack 8, adjustably mounted on the carriage 42, so as to normally engage with a pinion 9 connected to an escapement wheel 10. This 40 escapement wheel 10 is controlled in its movements, so as to give a step-by-step movement to the carriage 42, by a pair of pawls 11 and 12, one of which is fixed and the other of which is movable. These pawls 15 11 and 12 are mounted on a universal frame 13, so as to come alternately into engagement with the escapement wheel 10 when any one of the keys 1 and 2 is actuated. This is accomplished by a heel 14 on each 50 of the type bars 5 coming into engagement with a universal bar 15 on the universal frame 13. The universal frame 13 is supported for its back-and-forth movement by one or more arms 16, to which they are pivotally connected at 17, the latter being in turn pivoted at 18 to any suitable portion of the 55 typewriter frame.

The computing mechanism includes numeral keys 19, which act as described in my above mentioned application, to cause the

rotation of a shaft 20 from a shaft 21 by means of a complete gear 22 and a mutilated gear 23, amounts corresponding to the particular numeral keys actuated. Connected to each of the mutilated gears 23, there is 70 provided a one-tooth gear 24, which is arranged to rock a lever 201 to pull on a link 202, and thus draw down the associated one of the typewriter numeral keys 1 against the tension of a spring 203. The particular details of this mechanism are not essential to this invention, but may be the same as that shown and described in my above-mentioned application. The numeral 25 designates generally the totalizers or registers which 80 are mounted upon a suitable support 26 and each of the number bearing members of the totalizer or register is provided with a gear 27 by means of which motion may be imparted to the number bearing members. A 85 carriage 28 is mounted upon the base 29 of the mechanism so as to be reciprocated transversely thereof between suitable guides 30. Traveling actuating mechanism, designated generally by the reference numeral 31, 90 is supported by the carriage 28 to move therewith and the actuating mechanism embodies operating gears 32 for imparting motion to the gears 27. These gears 32 are connected with a shaft 33 and a gear 34 is also 95 provided on the shaft 33 which gear receives its motion from a drum or toothed cylinder 35 through the medium of intermediate gears 36.

The carriage 28 with the supported mechanism is adapted to be moved by means of an arm or lever 37 which is pivoted intermediate its ends as at 38 upon the base 29. This arm or lever 37 is preferably provided at one end with a toothed segment 39 which 100 meshes with a rack 40 carried by the carriage 28 so that when the arm or lever 37 is moved about its point of pivotal support 38 the carriage 28 will be correspondingly adjusted or moved to change the denominational relation of the gear 32 with respect to the gears 27 of the totalizers or registers 25.

All of the above described mechanism, however, forms no part of the present invention but constitutes a portion of the subject matter of the application above referred to.

The typewriter 41, which is shown in Figs. 17 and 21, is preferably supported at 120 an elevation above the base 29 and the carriage 42 thereof is provided with a rack 43 with which a pinion 44 on the end of an upright shaft 45 meshes and this shaft 45 is journaled in suitable bearings 46. As the 125 typewriter carriage 42 advances by the operation of the keys of the machine in the ordinary and well known manner, rotary motion is imparted to the shaft 45 through the rack and pinion 43, 44. This rotary motion of 130

the shaft 45 is caused to control the arm or lever 37 through the medium of the connecting mechanism which will now be described, so that the arm or lever 37 will move about its point of pivotal support in accordance with the movement of the typewriter carriage and thereby advance the traveling actuating mechanism 31 of the totalizers or registers.

- 10 Mounted loosely upon the shaft 45 (see particularly Figs. 8, 10, 14, 16 and 17) and preferably adjacent the base 29 of the machine is a gear 47 which meshes with a toothed segment 48 on the other end of the 15 arm or lever 37 which is adjacent thereto, and this gear 47 is connected to the shaft 45 for rotation therewith through the medium of a clutch, which clutch will lock the gear to the shaft when the shaft is rotating 20 in one direction and which may be rendered inactive to permit the gear or the shaft to be rotated in the opposite direction and independently with respect to each other according to whether the typewriter carriage 25 is returned independently with respect to the traveling actuating mechanism of the totalizer or vice versa. This clutch mechanism comprises a clutch member 49 (see particularly Figs. 6 and 8) which is sleeved as 30 upon the shaft 45 and is preferably keyed as at 50 to the shaft for rotation therewith. The clutch member is provided with a base 51 having a beveled or inclined face 52 and this inclined face is located some distance 35 above the bottom of the base 51 so that a smooth peripheral edge 53 will be provided for a purpose to be set forth. The clutch member above the inclined face 52 is preferably enlarged as at 54 and this enlarged 40 portion is provided with a notch 55 to form a shoulder 56 (see particularly Figs. 6 and 14). The body of the clutch member 49 above the enlarged portion 54 is preferably reduced as at 57 and this reduced portion 45 may be of any desired height. The periphery of the reduced portion is provided with spaced circumferential flanges or rings 58, for a purpose to be set forth. Secured to the gear 47, preferably the upper face 50 thereof and for rotation therewith, is a support 59 (see also Fig. 16), which preferably extends under the base 51 of the clutch member 49, and this support 59 is provided with extensions 60 projecting above the base and 55 on opposite sides of the clutch member 49. Pivottally mounted upon each of the extensions 60 is a dog or pawl 61 which are arranged on opposite sides of the clutch member 49 and are disposed in opposite directions. The extensions on the support 59 are of such a height that when the clutch member 57 is in an operative position so as to rest upon the support 59 between the extensions 60 to lock the shaft 45 and gear 47 60 together, the extremities of the dogs or pawls

61 will engage and rest against the periphery of the enlarged portion 54 of the clutch member, and elastic members 62 are provided for each of the dogs or pawls 61 which tend normally to hold the extremities thereof into engagement with the periphery of the portion 54.

The movements of the traveling actuating mechanism while controlled to take place step by step with the corresponding advancing movement of the typewriter carriage, are not effected by the carriage itself positively moving the traveling actuating mechanism. There is provided, however, a separate motive means for the traveling actuating mechanism, which normally tends to move the traveling actuating mechanism step by step in an advancing direction but is retarded by the carriage, which, however, as it moves along permits a corresponding movement of the actuating mechanism, which is forced by its separate motive means to follow the movements of the carriage just as soon as they are made. The means for doing this will now be described.

It will be manifest that as the typewriter carriage advances when the machine is being operated, in the usual direction, from right to left, the shaft 45 which is connected therewith will rotate in the direction indicated by the arrow in Fig. 14. It will also be manifest that in order to advance the traveling actuating mechanism in the same direction, the gear 47 which is connected with the arm or lever 37 must be rotated in a similar direction or in the direction indicated by the arrow in Fig. 14, but as the shoulder 56 on the clutch member 49 is so arranged that a rotation of the clutch member by the shaft 45 would tend to move the shoulder away from the adjacent dog or pawl 61, the gear 47 would remain idle inasmuch as it is loosely mounted on the shaft 45. Therefore in order to impart a rotation to the gear 47 in the same direction as the rotation of the shaft 45, suitable mechanism is provided and which mechanism will also tend to hold the extremity of one of the dogs or pawls 61 in engagement with the shoulder 56. Any suitable means may be provided for accomplishing this result but a suitable and efficient means comprising a motor will now be described.

A gear 63 preferably of the box type having a chamber 64 is journaled on a suitable axle 65 (reference being had particularly to Figs. 14 and 16). This axle 65 is mounted in a suitable support 66 and the gear 63 is adapted to rotate loosely thereon. This gear 63 meshes with the gear 47 and a spring 67 is arranged within the chamber 64 with one extremity 68 anchored to the wall of the chamber and the other extremity 69 is anchored to the axle 65 within the chamber. The spring 67 is coiled about the axle 65

in such a manner that its normal tendency will be to rotate the gear 63 in the direction indicated by the arrow in Fig. 14 and this movement of the gear 63 will tend to move the gear 47 in the direction indicated by the arrow in Fig. 14, and consequently the support 59 in a direction that the extremity of the dog or pawl 61 adjacent the shoulder 56 will be held in engagement with the shoulder, and the support 59 and the dog or pawl 61 will follow the clutch member 49. It will therefore be seen that the clutch just described will form a loose connection between the gear 47 and the shaft 45, that is to say, a connection which will cause the gear 47 to rotate in the same direction as the shaft 45, and will also permit either the shaft 45 or the gear 47 to be moved in the opposite direction one with respect to the other. The traveling actuating mechanism being connected with the gear 47 may also be returned to its initial or starting position independently with respect to the typewriter carriage 42. When the traveling actuating mechanism is thus returned, the dogs or pawls 61 will ride over the periphery of the enlarged portion 54 of the clutch member 49, the elastic members 62 actuating to cause the extremity of one of the dogs or pawls 61 to move into engagement with the shoulder 56 when the direction of movement of the dogs or pawls with respect to the clutch member 49 is reversed.

An arm 70 (see Figs. 3 and 16) may be provided on the axle 65 and which arm engages a stop 71 in order to hold the axle 65 against rotation under the tension of the elastic member or spring 67, and may be used to obtain an initial tension on the spring 67 in setting up the machine.

The typewriter carriage 42 is adapted to be automatically returned to its initial or starting position from any point to which it has been advanced and in order that this return may be effected at the will of the operator suitable mechanism for accomplishing this result will now be described. A shaft 72 is mounted in suitable bearings 73 so as to extend transversely with respect to the upright shaft 45 and this shaft 72 has connection with the shaft 45 (see particularly Figs. 3, 16 and 17) through the medium of a beveled gear 74 on the shaft 72 which meshes with a companion gear 75 on the shaft 45. A gear 76 (see particularly Figs. 3 and 4) is secured to the shaft 72 for rotation therewith, preferably at one end of the shaft and some distance from the gear 74. This gear 76 meshes with a gear 77 preferably of a larger diameter and which gear 77 is secured to a shaft 78 for rotation therewith, the latter being journaled in suitable bearings 79. A gear 80 is also secured to the shaft 78 for rotation therewith and meshing with this gear 80 is a toothed seg-

ment 81, which latter is formed on the end of an arm or lever 82 pivotally mounted intermediate its ends as at 83 to move about a horizontal axis so that the segment 81 will move in an upright plane. The free end 84 of the arm or lever 82 projects for some distance beyond the pivot 83 and is preferably bifurcated as at 85 (see particularly Fig. 3) across which bifurcation a projection 86 extends and if desired an anti-friction roller indicated in dotted lines at 87 in Fig. 4 is journaled on the projection 86. The extremity 84 of the arm 82 preferably terminates adjacent a shaft 88 which is journaled in suitable bearings 89 and secured to this shaft 88 for rotation therewith is a cam 90, which latter is so arranged as to project into the bifurcated portion 85 of the arm or lever 82 so as to permit the free end of the arm or lever 82 to be moved toward or away from the axis of rotation of the cam and to permit the periphery of the cam to engage the anti-friction roller 87 when the cam is rotated to force the free end of the arm or lever 82 away from the axis of rotation of the cam and thereby lower the segment 81 to rotate the gear 77 in one direction. The gear 77 is rotated in the opposite direction by the advancement of the typewriter carriage which will rotate the shaft 45 and the gear 75 thereon. This gear will impart its motion to the gear 74 on the shaft 72 and through the medium of the gear 76 on the shaft 72, the gear 77 will be moved in the opposite direction. This direction of rotation of the gear 77 will rotate the gear 80 which in turn will raise the segment 81 and move the extremity 84 of the arm or lever 82 toward the axis of rotation of the cam 90. The normal position of the cam 90 is such that the low portion thereof will be in the path of movement of the extremity 84 of the arm or lever while the high portion thereof will project into the bifurcated portion 85 of the arm or lever as shown clearly in Figs. 3 and 4. As the typewriter carriage advances, the arm or lever 82 will be automatically adjusted. It will therefore be manifest that in order to return the typewriter carriage 42 to its initial or starting position from any point to which it has advanced, all that is necessary is to raise the extremity 84 of the arm or lever 82 to lower the segment 81 and this may be accomplished by rotating the cam 90 about its axis of rotation. In order, therefore, to automatically control the rotation of the cam, suitable mechanism is provided which will now be described, reference being had particularly to Figs. 3, 4 and 5.

A running shaft 91 journaled in suitable supports 92 is provided and may derive its motion from any suitable source of power not necessary to illustrate. This shaft is preferably arranged parallel with and ad-

5 jacent to the shaft 88. A stub shaft 93 is arranged with one extremity adjacent one extremity of the running shaft 91 and the other extremity is journaled in a suitable bearing 94. The shaft 93 is connected to the running shaft 91 for rotation therewith through the medium of a gear 95 on the shaft 93 which meshes with a gear 96 on a supplemental shaft 97 and this shaft 97 is 10 in turn connected directly with the shaft 91 through the medium of a gear 98 meshing with a gear 99 on the shaft 91. Mounted loosely upon the shaft 93 is a gear 100 which meshes with a gear 101 fast on the shaft 88 15 to which the cam 90 is connected so that when the gear 100 is rotated the shaft 88 will be rotated through the medium of the gear 101, which rotation will rotate the cam 90. In order that the gear 100 may be 20 locked for rotation with the shaft 93, a clutch mechanism is provided which consists of a disk 102 (see also Fig. 7) secured to the gear 100 and which disk is also loosely mounted on the shaft 93. A star or toothed 25 wheel 103 is secured fast to the shaft 93 and rotates therewith and a dog or pawl 104 is pivotally mounted on the disk 102 so that one extremity 105 will engage the star or toothed wheel 103 and thereby lock the disk 30 102 to the shaft and consequently the gear 100. An elastic member 106 is also provided which tends normally to move the teeth 105 of the dog 104 into engagement with the extremity of the star or toothed wheel. 35 The dog or pawl 104 is provided with a shoulder 107 which is adapted to engage an arm 108 pivotally supported as at 109. When the extremity of this arm 108 is moved into the path of movement of the 40 shoulder 107 of the dog 104, the latter will be moved out of engagement with the star or toothed wheel 103 to release the gear 100 but when the extremity of the arm 108 is moved out of engagement with, or the path 45 of movement of, the shoulder 107, the elastic member 106 will move the extremity of the dog into engagement with the star or toothed wheel 103 to lock the gear 100 to the shaft 93.

50 A dog 110 is provided and is controlled by an elastic member 111 which latter tends normally to move the extremity of the dog into a notch 112 in the periphery of the disk 102 to lock the disk against overthrow. An 55 elastic member 113 tends normally to hold the extremity of the arm 108 into the path of movement of the shoulder 107 on the dog, and this arm is adapted to be moved out of engagement with the shoulder 107 so as to 60 lock the gear 100 to the shaft, at the will of the operator, by means of a suitable operating key 114 arranged in a convenient position for the operator. It will therefore be manifest that the rotation of cam 90 is controlled at the will of the operator by the

action of the key 114. When the key 114 is released, the elastic member 113 will return the latter and will also adjust the arm 108 to automatically release or unlock the gear 100 with respect to the shaft 93 without interrupting the rotation of the shafts 91, 93. As has been already stated the extremity 84 of the arm 82 during the advancement of the typewriter carriage is moved toward the axis of rotation of the cam 90 and whenever the cam 90 is rotated in the manner just set forth, the arm 82 will be moved to its normal or initial position to return the carriage from any point to which it has advanced.

70 In the present exemplification of the invention the traveling actuating mechanism of the registers is adapted to be advanced simultaneously with the typewriter carriage during nine steps of advancing movement of the typewriter carriage and to be automatically returned to its initial position 85 during the tenth step of the advancing movement of the typewriter carriage, and suitable mechanism for accomplishing this relative movement of the parts will now be described, 90 reference being had particularly to Figs. 3 and 8 to 16 inclusive.

75 Loosely mounted upon the shaft 45 and secured to the gear 47 for rotation therewith is a gear 115 with which a toothed segment 95 116 on an arm 117 meshes. This arm is pivotally supported intermediate its ends as at 118 and the free end 119 of the arm is adapted to be moved into and out of the path of movement of a cam 120 (see particularly 100 Figs. 3, 10 and 11), which cam is loosely mounted upon a shaft 121 having suitable bearings 122. The shaft 121 is rotated from a running shaft 123, which latter receives its motion from any suitable source. A gear 105 124 is secured to the shaft 123 for rotation therewith and meshes with a companion gear 125 on the shaft 121. The cam 120 is locked for rotation with the shaft 121 by means of a suitable dog 126 pivotally supported on a disk 127 which latter is loosely mounted on the shaft 121 and is connected with the cam 120 for rotation therewith. A star or toothed wheel 128 is secured to the shaft 121 for rotation therewith and the 115 dog 126 cooperates with this star or toothed wheel for locking the parts to the shaft. An elastic member 129 tends normally to move the dog 126 into engagement with the teeth of the star wheel and a shoulder 130 is provided on the dog. It will thus be seen that when the cam 120 is locked to the shaft 121, it will be rotated by the shaft and when the extremity 119 of the arm 117 is engaged by the cam 120, the arm will be rocked about 120 its point of pivotal support 118 to move the segment 116 and the movement of this segment 116 will rotate the gear 47 through the medium of the connecting gear 115.

125 As the gear 115 is connected to the gear 47 130

and as the latter follows up the movement of the shaft 45 so as to move therewith during the advancing movement of the typewriter carriage it will be manifest that the 5 traveling actuating mechanism will also be advanced through the medium of the arm 37 and as the gear 115 is rotated the segment 116 will be moved and consequently the arm 117 will be rocked about its point of pivotal 10 support and the extremity 119 of the arm will be moved into a position to be engaged by the cam 120.

A releasing dog or arm 131 is pivoted intermediate its ends as at 132 and its extremity 133 is provided with a shoulder adapted to engage the shoulder 130 on the dog 126 to hold the latter out of engagement with the star or toothed wheel 128. When this shoulder 133 is moved out of engagement with the shoulder 130, the elastic member 129 will adjust the dog 126 to lock the cam 120 to the shaft 121. The normal position of the arm 131 is that shown in Fig. 11 so that the cam 120 will unlock 25 with respect to the shaft 121.

As the typewriter carriage advances the arm or lever 37 will be moved in the direction indicated by the arrows in Fig. 3 so as to move a shoulder or projection 134 on 30 the segment 48 toward a pin or projection 135 on a link 136, which latter is supported by a bracket 137 for adjustment with respect thereto by means of a fastening pin 138 carried by the link 136 and which passes 35 through a slot 139 in the bracket 137. One end of this link 136 is pivotally connected as at 140 to the free end of the arm 131 and the pin or projection 135 is located at the free end of the link so as to project into the 40 path of movement of the shoulder 134 on the segment 48. The link 136 is of such a length that the segment 48 may be advanced nine steps during the nine steps of advancement of the typewriter carriage but during 45 the tenth step of advancement of the typewriter carriage, the shoulder 134 will be moved into engagement with the pin or projection 135 on the link 136 so as to shift the link and rock the arm 131 to release the dog 50 126 and thereby lock the cam 120 to the shaft 121 for rotation therewith. As the traveling actuating mechanism is thus returned the segment 48 will be moved in the opposite direction or the direction opposite 55 to that indicated by the arrows in Fig. 3, to move the shoulder 134 away from the pin or projection 135 and when the segment is thus adjusted the link 136 will be returned to permit the shoulder 133 on the arm 131 60 to be moved into the path of movement of the shoulder 130 of the dog 126 to trip the latter, by means of an elastic member 140 such as a spring or the like.

After the traveling actuating mechanism 65 has been returned to its initial or starting

position, the segment 48 of the arm 37 will have assumed the position shown in Fig. 3 and in order to prevent the motor comprising the gear 63 and the spring 67 from starting or moving the traveling actuating mechanism in a direction to advance the latter while the typewriter carriage is being returned so as to hold the actuating mechanism in its initial position, a stop 141 is provided (see particularly Figs. 3 and 18), 75 which consists of an elongated member preferably secured to the arm 37 to form a shoulder 142. A dog 143 is pivotally supported upon a fixed support 144 and moves between suitable guides 145 so that its extremity 146 will assume a position in the path of movement of the shoulder 142 and an elastic member 147 is provided which tends normally to move this extremity 146 into such position to be engaged by the shoulder and thereby lock the traveling actuating mechanism against movement. This dog 143 is connected through the medium of intermediate connecting mechanism designated generally by the reference numeral 80 204 with the escapement mechanism 7 of the typewriter carriage, so that each time a key is actuated and the typewriter carriage escapes, the dog 143 will be rocked and in the event that the extremity 146 95 stands within the path of movement of the shoulder 142, the dog will be raised to permit the segment 48 and the arm 37 to be advanced. After the shoulder 142 has passed the extremity 146 of the dog, this 100 extremity will engage and rest upon the top of the member 141. The connection 204 may be formed of a link 205 having a pin-and-slot connection with the dog 143, and an arm 206 connected to the link 205 and 105 fixed on the arm 16 of the escapement mechanism, so as to swing therewith at the actuation of any of the character keys. The lost motion between the link 205 and the dog 143 is provided so that the movement 110 of the escapement mechanism 7 will not be interfered with in case the dog 143 is riding on top of the stop 141.

It will therefore be manifest that during each tenth step of advancing movement of 115 the typewriter carriage the traveling actuating mechanism will be automatically returned to its initial or starting position, and in order to permit the typewriter carriage to be returned to its initial or starting 120 position independently with respect to the traveling actuating mechanism and without returning the traveling actuating mechanism, mechanism must be provided for preventing the automatic operation of the returning mechanism of the traveling actuating mechanism, which will now be described.

The clutch member 49 is adapted to be shifted longitudinally on the shaft 45 for the purpose already set forth by means of a 130

segment 148, (see particularly Figs. 3, 8 and 14) which is provided with teeth 149 meshing with the spaced rings or ribs 58 on the clutch member. This segment is secured to 5 a rock shaft 150 which latter is journaled in suitable bearings 151 and is provided with a segment 152 secured thereto (see also Fig. 4). This segment 152 meshes with a segment 153 on an arm 154 pivoted intermediate 10 its ends as at 155 to a support 156. The arm 154 is preferably arranged adjacent to and parallel with the arm 82 so that the extremity 157 of the arm will terminate adjacent the shaft 88 (see also Fig. 7) which 15 extremity is provided with a lateral projection 158 coöperating with a disk or cam 159 and an elastic member 160 tends normally to hold the extremity 157 of the arm 154 in engagement with the periphery of the cam. 20 This cam 159 is secured for rotation with the shaft 88 and the high part of the cam 159 is so disposed with respect to the high part of the cam 90 that when the shaft 88 is rotated motion will be imparted first to the 25 arm or lever 154 to rock the segment 152, rock shaft 150 and segment 148 to shift the clutch member 49 on the shaft 45 so as to present the smooth periphery 53 of the clutch member to the dogs or pawls 61 and 30 thereby unlock the gear 47 with respect to the shaft 45. A continued movement of the shaft 88 in the same direction will cause the cam 90 to then rock the arm 82 so as to rotate the shaft 72 and shaft 45 in a direction to return the typewriter carriage 42. When the low part of the cam 159 is in proximity to the projection 158 on the arm 154, the elastic member 160 will rock the shaft 150 in the opposite direction and consequently move the segment 148 in the opposite direction to shift the clutch member 49 into a position to again lock the gear 47 to the shaft 45. 35 As has already been stated, the traveling 45 actuating mechanism will be automatically returned during the tenth step of advancing movement of the typewriter carriage by the engagement of the shoulder 134 with the pin or projection 135 on the link 136 which shifts the arm 131 so that the cam 120 will be locked to the shaft 121. Therefore in the event that it is desired to permit the traveling actuating mechanism to remain in the position to which it has advanced and 50 to return the typewriter carriage independently with respect to the traveling actuating mechanism it is necessary to prevent the engagement of the shoulder 134 with the pin or projection 135 on the link 136 as the engagement of these parts during 55 this operation might cause damage to the machine. Mechanism is therefore provided to arrest the movement of the segment 48 before the shoulder 134 engages the pin or projection 135 on the link 136 and prefer- 60 ably comprises an arm 161 (see particularly Figs. 3, 8, 15 and 16) which is connected to the shaft 150 and is so disposed with respect to the segment 148 that when the latter is adjusted to shift the clutch member 49 on the shaft 45 to unlock the gear 47 therefrom, the arm will be moved into the path of movement of a second shoulder 162 on the segment 48, and which shoulder engages the arm before the shoulder 134 will engage the pin or projection 135 on the link 136. The normal position of the arm 161 is elevated, or a position out of the path of movement of the shoulder 162, which position it will assume when the clutch member 49 is moved into operating position to lock the gear 47 to the shaft 45. 70 If desired, a dog 163 may be provided which coöperates with a notch 164 in the periphery of the disk 127 (see Figs. 8 and 11) for holding the disk 127 in position when unlocked from the shaft 121 and an elastic member 165 is also provided which tends normally to hold the dog 163 against the periphery of the disk. 75 From the above description it is thought that the operation of all the parts will be clearly understood, but briefly stated it is as follows: 80 As the typewriter carriage 42 advances motion will be imparted to the shaft 45 and the arm 37 will be rocked about its pivot 38 to advance the carriage 28 upon which the traveling actuating mechanism of the totalizers is mounted. The carriage 28 will be advanced step by step by the advancement of the typewriter carriage 42 during nine steps of advancing movement of the latter and as the arm 37 is moved about its pivot 38 the shoulder 134 on the segment 48 will be moved toward the pin or projection 135 on the link 136. During this movement of the parts the arm 117 will be rocked about its point of pivotal support 118 to move the extremity 119 thereof into the path of movement of the cam 120, which latter is loose on its shaft. During the tenth step of advancing movement of the typewriter carriage the shoulder 134 will engage the pin or projection 135 on the link 136 and shift the latter to rock the arm 131, thus releasing the dog 126 and locking the cam 120 to the shaft 121. Thus locked motion will be imparted from the running shaft 123 to the cam 120 and the arm 117 will be rocked in the opposite direction to rotate the gear 47 in the opposite direction, which movement is permitted by means of the dogs or pawls 61 sliding around the periphery of the portion 54 of the clutch member 49. This reverse movement of the gear 47 will rock the arm 37 in the opposite direction and return the computing carriage 28. 90 During the advancing movement of the typewriter carriage motion will also be im- 95 100 105 110 115 120 125 130

parted to the shaft 72 to move the extremity 84 of the arm 82 toward the axis of rotation of the cam 90.

When it is desired to return the typewriter carriage to its initial starting position from any point to which it has advanced, the key 114 may be actuated which will rock the arm 108 to release the dog 104 to lock the gear 100 to the running shaft 93. Thus 10 locked the gear 100 will rotate the cam 90 to shift the arm 82 in the opposite direction and thereby rotate the shaft 72 in the opposite direction as well as the shaft 45 to return the typewriter carriage.

15 When the key 114 is actuated to return the typewriter carriage, the rotation of the shaft 88 will also rotate the cam 159 and this will rock the shaft 150 to shift the clutch member 49 to release the gear 47 and at the 20 same time move the arm 161 into the path of movement of the shoulder 162 on the segment 48 to arrest the movement of the segment before the shoulder 134 strikes the projection 135 to prevent the cam 120 from being 25 locked to the shaft 121.

The device is also capable of cross-addition. For example, we may start with the carriage at the right and write a series of digits comprising a number in the first 30 column on the work-sheet, and these digits may be run up successively even on a single computing register or totalizer 25, as the traveling, actuating mechanism, including the master wheel 32, moves step by step with 35 the step-by-step letter-feeding movement of the typewriter carriage. When the entire number in this first column has been written, the limit being in this case nine digits corresponding to nine step-by-step movements of the typewriter carriage, then a further movement of the typewriter carriage will cause the automatic return of the computing carriage with its master wheel, so that the computing mechanism is ready 45 to run up the digits of a fresh number. The typewriter carriage, however, can travel on without returning to bring the next columnar space on the work-sheet up to the printing point when the next number, comprising 50 a series of digits, can be inscribed thereon and concomitantly run up on the computing register or totalizer 25. This can be repeated within the limits of the work-sheet and the travel of the typewriter carriage. 55 When the line is completed we have cross-added in the computing register or totalizer, a series of different numbers of different columns arranged in the same horizontal line. When the end of the line has been reached, 60 the key 114 can be depressed to enable a complete return movement of the carriage to its original starting position. The typewriter platen can then be spaced to bring a fresh line of the work-sheet up to the printing point and the operation repeated as

often as desired. By this arrangement, then, we may have repeated vibrations of the traveling element of the computing mechanism during one single continuous travel of the typewriter carriage from left to right.

Certain features disclosed in this application are also disclosed in somewhat different forms, and broadly claimed, in my prior applications, Serial Nos. 236,498, filed December 12, 1904, 302,845, filed February 26, 1906, and 504,595, filed June 26, 1909. Application Serial No. 236,498 is directed, among other things, to a series of column-totalizers, a cross-totalizer, a grand-totalizer, and actuating mechanism for said totalizers, including reversing mechanism. Application Serial No. 302,845 is directed, among other things, to a somewhat different arrangement of totalizers and actuating mechanism, including reversing mechanism, for effecting column-footing and cross-footing, and for accumulating a grand-total, concomitantly with the writing of a series of numbers in different columns on a work-sheet. Application Serial No. 504,595 is directed, among other things, to a plurality of column-totalizers, a cross-totalizer, a grand-totalizer, and means whereby any one of said column-totalizers may be operated concomitantly with either said cross-totalizer or said grand-totalizer. It also comprises means for concomitantly operating said cross-totalizer and said grand-totalizer. It also comprises actuating mechanism for said totalizer consisting of a set of motor-driven key-controlled mutilated gears for rotating the computing wheels amounts determined in accordance with any particular number key depressed. In the present application, I do not claim any of the features common thereto and to any of the above-mentioned applications, the claims in this case being restricted to features not disclosed in any of said prior applications.

What is claimed as new is—

1. In a calculating machine, the combination with a typewriter carriage adapted for advancement, and a computing unit having a traveling element with a supporting carriage therefor, of means for advancing the typewriter carriage and supporting carriage together, a motor normally inactive for returning said supporting carriage, and means for bringing said motor into operation at a predetermined point in the advancement of said carriages.

2. In a calculating machine, the combination of a typewriter carriage adapted for advancement, a computing unit having a traveling element with a supporting carriage therefor, separate means for advancing said typewriter carriage and said supporting carriage, means enabling said carriages to travel together during said ad-

vancement, and means individual to each carriage for independently returning the same.

3. In a calculating machine, the combination of a typewriter carriage adapted for advancement, a computing unit having a traveling element with a supporting carriage therefor, separate means for advancing said carriages, means enabling said carriages to travel together when thus advanced, normally inactive means for returning said supporting carriage, means brought into action at a predetermined point in the advancement of said carriages for rendering said supporting-carriage-returning means active, means for disconnecting said typewriter carriage from said supporting carriage at any point in the joint travel of said carriages, and means for returning said typewriter carriage when thus disconnected.

4. In a calculating machine, the combination of a typewriter carriage adapted for advancement, a computing unit having a traveling element with a supporting carriage therefor, means for advancing said carriages together, means for automatically disconnecting the typewriter carriage from said supporting carriage and returning said typewriter carriage from any point of its advancement, and means for preventing said supporting carriage from being returned during the return of the typewriter carriage.

5. In a calculating machine, the combination of a typewriter carriage adapted for advancement, a computing unit having a traveling element with a supporting carriage therefor, means to advance said carriages together, said means permitting independent return of said supporting carriage, means normally inactive for returning said supporting carriage to normal position after a predetermined joint advance movement of said carriages, an escapement for said typewriter carriage, means for holding said supporting carriage in its normal position on its return independently of the typewriter carriage, and means controlled from said escapement for releasing said holding means.

6. In a calculating machine, the combination of a typewriter carriage adapted for advancement, a computing unit having a traveling element with a supporting carriage adapted for advancement, means embodying a normally inactive coupling for returning the said supporting carriage independently with respect to the typewriter carriage, and means adapted to be actuated when the typewriter carriage reaches a predetermined point in its advancement for rendering the said coupling active.

7. In a calculating machine, the combination of a typewriter carriage adapted for advancement, a computing unit embodying actuating mechanism and a supporting carriage for the latter, means for advancing

the supporting carriage, means embodying a normally inactive coupling for returning the carriage to its initial or starting position independently of the typewriter carriage, means actuated by the advancement of the supporting carriage for rendering the said coupling active when the supporting carriage reaches a predetermined point in its advancement, means for returning the typewriter carriage, and means for maintaining the said coupling inactive when the typewriter carriage is returned.

8. In a calculating machine, the combination of a typewriter carriage adapted for advancement, a computing unit embodying actuating mechanism and a supporting carriage for the latter, means for advancing the supporting carriage, means embodying a normally inactive coupling for returning the supporting carriage to its initial or starting position independently of the typewriter carriage, means actuated by the advancement of the supporting carriage for rendering the said coupling active when the supporting carriage reaches a predetermined point in its advancement, means for returning the typewriter carriage, and means for arresting the advancing movement of the supporting carriage to maintain the coupling inactive during the return of the typewriter carriage.

9. In a calculating machine, the combination of a typewriter carriage adapted for advancement, a computing unit embodying actuating mechanism and a supporting carriage for the latter, means for advancing the supporting carriage, means embodying a normally inactive coupling for returning the supporting carriage independently with respect to the typewriter carriage, means adapted to be actuated when the typewriter carriage reaches a predetermined point in its advancement for rendering the said coupling active, and means for automatically rendering the coupling inactive.

10. In a calculating machine, the combination of a typewriter carriage adapted for advancement, a computing unit embodying actuating mechanism and a supporting carriage for the latter, means for advancing the supporting carriage in unison with the typewriter carriage, means adapted to be set by the advancement of the supporting carriage for returning the latter, means for actuating the last recited means to return the supporting carriage independently of the typewriter carriage and embodying a normally inactive coupling, and means adapted to be automatically actuated when the typewriter carriage reaches a predetermined point in its advancement for rendering the coupling active.

11. In a calculating machine, the combination of a typewriter carriage adapted for advancement, a computing unit embody-

- ing actuating mechanism and a supporting carriage for the latter, means for advancing the supporting carriage in unison with the typewriter carriage, means adapted to be set by the advancement of the supporting carriage for returning the latter, means for actuating the last recited means to return the supporting carriage independently of the typewriter carriage and embodying a normally inactive coupling, means adapted to be automatically actuated when the typewriter carriage reaches a predetermined point in its advancement for rendering the coupling active, means adapted to be set by the advancement of the typewriter carriage for returning the latter from any point to which it has advanced independently with respect to the said supporting carriage, and means for maintaining the said coupling inactive when the typewriter carriage is thus returned.
12. In a calculating machine, the combination of a typewriter carriage adapted for advancement, a computing unit embodying actuating mechanism and a supporting carriage for the latter, means for advancing the supporting carriage in unison with the typewriter carriage, means adapted to be set by the advancement of the supporting carriage for returning the latter, means for actuating the last recited means to return the supporting carriage independently of the typewriter carriage and embodying a normally inactive coupling, means adapted to be automatically actuated when the typewriter carriage reaches a predetermined point in its advancement for rendering the coupling active, and means for automatically rendering the coupling inactive.
13. In a calculating machine, the combination of a typewriter carriage adapted for advancement, a computing unit embodying actuating mechanism and a supporting carriage for the latter, means for advancing the supporting carriage in unison with the typewriter carriage, means adapted to be set by the advancement of the supporting carriage for returning the latter, means for actuating the last recited means to return the supporting carriage independently of the typewriter carriage and embodying a normally inactive coupling, means adapted to be automatically actuated when the typewriter carriage reaches a predetermined point in its advancement for rendering the coupling active, means adapted to be set by the advancement of the typewriter carriage for returning the latter from any point to which it has advanced, means for controlling the last said means at will, and means adapted to be set by the actuation of the last recited controlling means for maintaining the said coupling inactive.
14. In a calculating machine, the combination of a typewriter carriage adapted for advancement, a computing unit embodying actuating mechanism and a supporting carriage for the latter, means for advancing the supporting carriage in unison with the typewriter carriage, means adapted to be set by the advancement of the typewriter carriage for returning the latter from any point to which it has advanced, means for controlling the last recited means at will, a stop adapted to be set by the actuation of the last recited supporting carriage in unison with the typewriter carriage, means adapted to be set by the advancement of the supporting carriage for returning the latter, means for actuating the last recited means to return the supporting carriage independently of the typewriter carriage and embodying a normally inactive coupling, means adapted to be automatically actuated when the typewriter carriage reaches a predetermined point in its advancement for rendering the coupling active, means adapted to be set by the advancement of the typewriter carriage for returning the latter from any point to which it has advanced, means for controlling the last said means at will, and means operatively related to the last recited means for maintaining the said coupling inactive.
15. In a calculating machine, the combination of a typewriter carriage adapted for advancement, a computing unit embodying actuating mechanism and a supporting carriage for the latter, means for advancing the supporting carriage in unison with the typewriter carriage, means adapted to be set by the advancement of the supporting carriage for returning the latter, means for actuating the last recited means to return the supporting carriage independently of the typewriter carriage and embodying a normally inactive coupling, means adapted to be automatically actuated when the typewriter carriage reaches a predetermined point in its advancement for rendering the coupling active, means adapted to be set by the advancement of the typewriter carriage for returning the latter from any point to which it has advanced, means for controlling the last said means at will, and means operatively related to the last recited means for maintaining the said coupling inactive.

controlling means for maintaining the said coupling inactive, and means for restoring the stop to an inoperating position.

17. In a calculating machine, the combination of a typewriter carriage adapted for advancement, a computing unit having a traveling element with a supporting carriage therefor, means for advancing the supporting carriage in unison with the typewriter carriage, said advancing means enabling the concomitant return movement of the supporting carriage with the return movement of the typewriter carriage, means for returning the typewriter carriage independently with respect to the supporting carriage, and means for disconnecting the typewriter carriage from the supporting carriage prior to such independent return movement of the typewriter carriage.

18. In a calculating machine, the combination of a typewriter carriage adapted for advancement, a computing unit embodying actuating mechanism and a supporting carriage for the latter, means for advancing the supporting carriage, means enabling the return of the supporting carriage with the typewriter carriage when the latter is returned, said last mentioned means embodying a clutch permitting independent return of the supporting carriage with respect to the typewriter carriage, means for returning the supporting carriage independently with respect to the typewriter carriage when the latter has reached a predetermined point in its advancement, means for returning the typewriter carriage independently with respect to the supporting carriage, and means for disconnecting the typewriter carriage from the supporting carriage to permit such independent return of the typewriter carriage.

19. In a calculating machine, the combination of a typewriter carriage adapted for advancement, a computing unit embodying actuating mechanism and a supporting carriage for the latter, means for advancing the supporting carriage, means enabling the return of the supporting carriage with the typewriter carriage when the latter is returned, said connecting means embodying a clutch permitting independent return of the supporting carriage with respect to the typewriter carriage, means for returning the supporting carriage independently with respect to the typewriter carriage when the latter has reached a predetermined point in its advancement, means for returning the typewriter carriage independently with respect to the supporting carriage, means for disconnecting the typewriter carriage from the supporting carriage to permit such independent return of the typewriter carriage, and means for restraining the supporting carriage against advancement when the

typewriter carriage is disconnected therefrom.

20. In a calculating machine, the combination of a typewriter carriage adapted for advancement, a computing unit embodying actuating mechanism and a supporting carriage for the latter, means for advancing the supporting carriage, means enabling the return of the supporting carriage with the typewriter carriage when the latter is returned, said last mentioned means embodying a clutch permitting independent return of the supporting carriage with respect to the typewriter carriage, means for returning the supporting carriage independently with respect to the typewriter carriage when the latter has reached a predetermined point in its advancement, means adapted to be set by the advancement of the typewriter carriage for returning the latter to its initial or starting position from any point to which it has advanced and independently with respect to the said supporting carriage, means for controlling the last said means at will, and means also controlled by the said controlling means for disconnecting the typewriter carriage and the supporting carriage to permit such independent return of the typewriter carriage.

21. In a calculating machine, the combination of a typewriter carriage adapted for advancement, a computing unit embodying actuating mechanism and a supporting carriage for the latter, means for advancing the supporting carriage, means enabling the return of the supporting carriage with the typewriter carriage when the latter is returned, said last-mentioned means embodying a clutch permitting independent return of the supporting carriage with respect to the typewriter carriage, means for returning the supporting carriage independently with respect to the typewriter carriage when the latter has reached a predetermined point in its advancement, means adapted to be set by the advancement of the typewriter carriage for returning the latter to its initial or starting position from any point to which it has advanced and independently with respect to the said supporting carriage, means for controlling the last said means at will, means also controlled by the said controlling means for disconnecting the typewriter carriage and the supporting carriage to permit such independent return of the typewriter carriage, means for returning the supporting carriage, and means for automatically controlling the last recited means.

22. In a calculating machine, the combination with a typewriter carriage adapted for advancement, and a computing unit having a traveling element with a supporting carriage therefor, of mechanism for advancing said carriages together, said mecha-

nism including means operatively connecting the typewriter carriage and the supporting carriage, whereby, when said typewriter carriage is manually returned, it will return
 5 said supporting carriage, means for automatically returning said typewriter carriage, and means for disconnecting said typewriter carriage from said supporting carriage when said automatic returning means is
 10 brought into operation.

23. In a calculating machine, the combination of a typewriter carriage adapted for advancement, a computing unit embodying actuating mechanism and a supporting carriage for the latter, means for advancing the supporting carriage, means operatively connecting the typewriter carriage and the supporting carriage whereby one will be returned to its initial or starting position by
 15 the return movement of the other, means adapted to be set by the advancement of each of the said typewriter carriage and supporting carriage for returning them separately one with respect to the other, and
 20 means for controlling the last recited means.

24. In a calculating machine, the combination of a typewriter carriage adapted for advancement, a computing unit embodying actuating mechanism and a supporting carriage for the latter, means for advancing the supporting carriage, means operatively connecting the typewriter carriage and the supporting carriage whereby one will be returned to its initial or starting position by
 25 the return movement of the other, means adapted to be set by the advancement of each of the said typewriter carriage and supporting carriage for returning them separately one with respect to the other, means
 30 for automatically controlling one of the said returning means, and means for controlling the other of the said returning means at will.

25. In a calculating machine, the combination of a typewriter carriage adapted for advancement, a computing unit embodying actuating mechanism and a supporting carriage for the latter, means for advancing the supporting carriage, means operatively
 35 connecting the typewriter carriage and the supporting carriage whereby one will be returned to its initial or starting position by the return movement of the other, means adapted to be set by the advancement of each of said carriages for returning them separately one with respect to the other, means for controlling the last recited means and mechanism for locking one of the said returning means against actuation during
 40 the operation of the other of the said returning means.

26. In a calculating machine, the combination of a typewriter carriage adapted for advancement, a computing unit embodying actuating mechanism and a supporting car-

riage for the latter, means for advancing the supporting carriage, means connecting the supporting carriage with the typewriter carriage for return movement thereby, the last said means serving to control the advancement of the supporting carriage, and means for returning the said typewriter carriage and the supporting carriage separately one with respect to the other and embodying means for rendering the said connecting means inactive.

27. In a calculating machine, the combination of a typewriter carriage adapted for advancement, a computing unit embodying actuating mechanism and a supporting carriage for the latter, means for advancing the supporting carriage, means connecting the supporting carriage with the typewriter carriage for return movement thereby and embodying a shiftable clutch element, and means for returning the said typewriter carriage and the supporting carriage separately one with respect to the other and embodying means for shifting the clutch element to render the said connection inactive.

28. In a calculating machine, the combination of a typewriter carriage adapted for advancement, a computing unit embodying actuating mechanism, a supporting carriage for the latter, means for advancing the supporting carriage, means connecting the supporting carriage with the typewriter carriage for return movement by the return of the latter and embodying a shiftable clutch element, means for automatically returning the said supporting carriage to its initial or starting position when the typewriter carriage reaches a predetermined point in its advancement and independently with respect to the typewriter carriage, means for returning the typewriter carriage to its initial or starting position independently with respect to the supporting carriage and embodying means for shifting the said clutch element, and means for locking the supporting carriage in the position to which it has been returned and while the typewriter carriage is returned.

29. In a calculating machine, the combination of a typewriter carriage adapted for advancement, a computing unit embodying actuating mechanism, a supporting carriage for the latter, means for advancing the supporting carriage, means connecting the supporting carriage with the typewriter carriage for return movement by the return of the latter and embodying a shiftable clutch element, means for automatically returning the said supporting carriage to its initial or starting position when the typewriter carriage reaches a predetermined point in its advancement and independently with respect to the typewriter carriage, means for returning the typewriter carriage to its initial or starting position independently with respect to the supporting carriage and embodying means for shifting the said clutch element, and means for locking the supporting carriage in the position to which it has been returned and while the typewriter carriage is returned.

respect to the supporting carriage and embodying means for shifting the said clutch element, means for locking the supporting carriage in the position to which it has been returned and while the typewriter carriage is returned, and means operatively related to the typewriter carriage for automatically releasing the supporting carriage.

30. In a calculating machine, the combination of a typewriter carriage adapted for advancement, a computing unit embodying actuating mechanism, a supporting carriage for the latter, means for advancing the supporting carriage, means connecting the supporting carriage with the typewriter carriage for return movement by the return of the latter and embodying a shiftable clutch element, means for automatically returning the said supporting carriage to its initial or starting position when the typewriter carriage reaches a predetermined point in its advancement and independently with respect to the typewriter carriage, means for returning the typewriter carriage to its initial or starting position independently with respect to the supporting carriage and embodying means for shifting the said clutch element, and means for locking the supporting carriage returning means against actuation during the actuation of the typewriter carriage returning means.

31. In a calculating machine, the combination of a typewriter carriage adapted for advancement, a computing unit embodying actuating mechanism, a supporting carriage for the latter, means for advancing the supporting carriage, means connecting the supporting carriage with the typewriter carriage for return movement by the return of the latter and embodying a shiftable clutch element, means for automatically returning the said supporting carriage to its initial or starting position when the typewriter carriage reaches a predetermined point in its advancement and independently with respect to the typewriter carriage, means for returning the typewriter carriage to its initial or starting position from any point to which it has advanced, and independently with respect to the supporting carriage, the last recited means embodying means for shifting the said clutch element, and means for arresting the advancement operation of the said supporting carriage when the typewriter carriage is being returned.

32. In a calculating machine, the combination of a typewriter carriage adapted for advancement, a computing unit embodying actuating mechanism, a supporting carriage for the latter, means for advancing the supporting carriage, means connecting the supporting carriage with the typewriter carriage for return movement by the return of the latter and embodying a shiftable

clutch element, means for automatically returning the said supporting carriage to its initial or starting position when the typewriter carriage reaches a predetermined point in its advancement and independently with respect to the typewriter carriage, means for returning the typewriter carriage to its initial or starting position from any point to which it has advanced, and independently with respect to the supporting carriage, the last recited means embodying means for shifting the said clutch element, means for controlling the typewriter carriage returning means at will, and means for arresting the advancement operation of the said supporting carriage when the typewriter carriage is being returned.

33. In a calculating machine, the combination of a typewriter carriage adapted for advancement, a computing unit embodying actuating mechanism and a supporting carriage for the latter, means for advancing the supporting carriage, means connecting the supporting carriage with the typewriter carriage for return movement thereby, the last said means embodying a clutch for locking the parts when the supporting carriage and typewriter carriage are being advanced, and means for thus returning the supporting carriage, said clutch embodying an element having a shoulder and an element co-operating with the shoulder, the last said element yielding to permit the supporting carriage to be independently returned with respect to the typewriter carriage.

34. In a calculating machine, the combination of a typewriter carriage adapted for advancement, a computing unit embodying actuating mechanism and a supporting carriage for the latter, means for advancing the supporting carriage, means connecting the supporting carriage with the typewriter carriage for return movement thereby, the last said means embodying a clutch for locking the parts when the supporting carriage and typewriter carriage are being advanced, means for thus returning the supporting carriage, said clutch embodying an element having a shoulder and an element co-operating with the shoulder, the last said element yielding to permit the supporting carriage to be independently returned with respect to the typewriter carriage, and means for displacing said shoulder and the co-operating clutch element, one with respect to the other to permit the typewriter carriage to be returned independently with respect to the said supporting carriage.

35. In a calculating machine, the combination with a typewriter carriage adapted for advancement, and a computing unit having a traveling element with a supporting carriage therefor, of means including a rotatable shaft for retracting said typewriter carriage, means for advancing said support-

ing carriage including a gear loosely mounted on said shaft, a clutch member secured to the shaft for rotation therewith and for longitudinal adjustment thereon, interengaging 5 means operatively related to the gear and to the clutch member, means coöperating with the gear for holding said last mentioned means in engagement, and means for laterally displacing one of said interengaging 10 means with respect to the other to permit the shaft to be rotated independently with respect to the gear and in the opposite direction, so as to enable said typewriter carriage to be returned to normal position independently 15 of said supporting carriage.

36. In a calculating machine, the combination with a typewriter carriage adapted for advancement, and a computing unit having a traveling element with a supporting 20 carriage therefor, of means including a rotatable shaft for retracting said typewriter carriage, means for advancing said supporting carriage including a gear loosely mounted on said shaft, a clutch member secured to said shaft for rotation therewith and for longitudinal adjustment with respect thereto, said clutch member being provided with a shoulder, a clutch member controlled by the gear and adapted to engage the shoulder, 25 means coöperating with the gear for normally holding said last clutch member and shoulder in engagement, whereby the shaft and gear will rotate in the same direction, so that said typewriter carriage and said supporting carriage may move step by step together, said means coöperating with the gear permitting the gear to be rotated in the opposite direction independently of the shaft, and means for shifting said first clutch member 30 on the shaft to laterally displace the same with respect to the coöperating clutch member, whereby the shaft may be rotated in the opposite direction independently with respect to the gear, so as to enable the typewriter carriage to return independently of the supporting carriage.

37. In a calculating machine, the combination with a typewriter carriage adapted for advancement, and a computing unit having a traveling element with a supporting carriage therefor, of means including a rotatable shaft for retracting said typewriter carriage, means for advancing said supporting carriage including a gear loosely mounted on said shaft, a clutch member mounted on the shaft for rotation therewith and for longitudinal adjustment with respect thereto, and being provided with a shoulder, a yielding member operatively connected with the gear and coöperating with the shoulder to hold the parts for simultaneous rotation in one direction, so that said supporting carriage will move step by step with said typewriter carriage, means coöperating with the

gear, and tending normally to rotate the gear in the same direction with the shaft and for holding the yielding member in engagement, a cam on said clutch member, and means for shifting the latter so that the cam engages the yielding member to move the latter out of engagement with the shoulder, to permit the shaft to be rotated in the opposite direction and independently with respect to the gear, to enable the typewriter carriage to be returned to normal position independently of the supporting carriage. 70 75

38. The combination with a traveling typewriter carriage, of computing mechanism having a traveling carriage, means for causing said carriages to move concomitantly in an advancing direction, means for returning said computing mechanism carriage, and means for positively preventing the said returning means from acting while the typewriter carriage is moving in a return direction. 80 85

39. The combination with typewriting mechanism, of calculating mechanism co-operating with said typewriting mechanism, both of said mechanisms having each a traveling element and connections to enable said traveling elements to coöperate with each other so that their movement in one direction will be interdependent and their movement in the opposite direction independent, and means for preventing the movement of one of said elements in one direction while the other element is moving. 90 95

40. The combination with typewriting mechanism having a traveling element, of computing mechanism having a traveling element of said computing mechanism, connections to enable the traveling element of said typewriting mechanism to control the traveling movement of the traveling element of said computing mechanism, means for freeing said traveling element of said computing mechanism from control by said traveling element of said typewriting mechanism, and a lock for said traveling element of said computing mechanism brought into play at the freeing of said traveling element of said computing mechanism from control by the traveling element of said typewriting mechanism. 100 105 110 115

41. The combination with a typewriter carriage, of computing mechanism having a traveling element, a lock for preventing the movement of said traveling element, connections to enable the control of the movement of said traveling element by said carriage, and a lock for preventing a movement of said traveling element during a certain movement of said carriage. 120 125

42. The combination with typewriting mechanism including a carriage and an escapement for said carriage, of computing

mechanism having a traveling element, a lock for said traveling element, connections to enable the movements of said traveling element to be controlled by said carriage, a second lock for preventing a certain movement of said traveling element during a certain movement of said carriage, and means to enable said escapement to control one of said locks.

43. The combination with computing mechanism having a traveling element, of means for traversing said traveling element, typewriting mechanism having a carriage with an escapement therefor, a lock for preventing a certain movement of said traveling element, and means to enable said escapement to control the effectiveness of said lock.

44. The combination with computing mechanism having a traveling element, of a motor for traversing said traveling element, a typewriter carriage, connections enabling the concomitant movement of said traveling element and said typewriter carriage, said connections including a clutch between said motor and said typewriter carriage, and means for shifting said clutch to an ineffective position so as to prevent the actuation of said motor with said typewriter carriage during a certain movement thereof.

45. The combination with computing mechanism including a traveling element, of a typewriter carriage, a spring motor for enabling said traveling element to move according to the movement of said carriage in a letter-feeding direction, connections enabling said carriage to obstruct the movement of said traveling element until it itself moves, and disconnecting means for said connections to prevent said carriage during its return movement from winding up said spring motor.

46. The combination with computing mechanism including a traveling element, of a typewriter carriage, a spring motor for enabling said traveling element to move according to the movement of said carriage in a letter-feeding direction, connections enabling said carriage to obstruct the movement of said traveling element until it itself moves, disconnecting means for said connections to prevent said carriage during its return movement from winding up said spring motor, and means distinct from said carriage for winding up said spring motor.

47. The combination with computing mechanism having a traveling element, of typewriting mechanism having a carriage, connections for enabling said carriage to obstruct the movement of said traveling element until said carriage itself moves in a letter-feeding direction, said connections enabling the independent return of said traveling element with respect to said carriage,

and means for interrupting said connections 65 to enable the independent return of said carriage with respect to said traveling element.

48. The combination with a traveling typewriter carriage, of a computing mechanism 70 having a traveling element to enable successive denominational actions of said computing mechanism, connections enabling the advance of said traveling element with the typewriter carriage, driving connections 75 driven by a source of power independent of said carriage, for traversing said traveling element, and automatic means coming into play after a predetermined movement of said traveling element with said carriage, to 80 cause said driving connections to traverse said traveling element independently of said carriage.

49. The combination with a typewriter carriage, of a computing mechanism having 85 a traveling element to enable denominational selections in computing actions of said computing mechanism, connections enabling said traveling element to advance step by step with the advancing movement of said carriage, means for automatically and repeatedly returning said traveling element relatively to said carriage during a continuous advancing movement of said carriage at the end of predetermined advancing movements 95 of said traveling element with said carriage, and automatic means for returning said typewriter carriage after a predetermined continuous advancing movement corresponding to several repeated advancing movements of said traveling element.

50. The combination with a traveling carriage, of a computing mechanism having a traveling element, connections to enable a concomitant travel of said traveling element with the travel of said carriage, independent driving gearing for traversing said carriage, and independent driving gearing for traversing said traveling element.

51. The combination with a traveling carriage, of a computing mechanism having a traveling element, connections to enable a concomitant travel of said traveling element with the travel of said carriage, independent driving gearing for traversing said carriage, independent driving gearing for traversing said traveling element, and locking means for positively preventing a driving action of one of said driving gearings 110 while the other of said driving gearings is in 115 action.

52. The combination with a computing mechanism including a traveling element having a step-by-step movement to select denominations, of a train of gearing for traversing said element, a traveling typewriter carriage connected to control the advancing movement of said traveling element, and

- means for concomitantly disconnecting said traveling element with respect to said carriage and preventing the drive of said traveling element by said train of gearing.
5. 53. The combination with a computing mechanism including a traveling element, of a normally silent train of gearing for traversing said traveling element, and means for bringing said train of gearing into driving action after a predetermined movement of said traveling element, the extent of driving action by said train of gearing being dependent on the previous movement of said traveling element.
10. 54. The combination with a computing mechanism including a traveling element having a step-by-step movement to determine denomination selections, of a traveling typewriter carriage, the movements of said traveling element according with the step-by-step movements of said carriage, an escapement mechanism for said typewriter carriage, and means controlled from said escapement mechanism for governing a movement of said traveling element.
15. 55. In a calculating machine having the usual typewriter carriage adapted for advancement, the usual totalizer and denomination-selecting means therefor, a supporting carriage for one of these elements, means separate from the typewriter-carriage-advancing means for advancing the said supporting carriage, means connecting the typewriter carriage and the supporting carriage for advancement in unison, and means for maintaining said supporting carriage in its initial or starting position during the return movement of the typewriter carriage.
20. 56. In a calculating machine, the combination with a typewriter carriage adapted for advancement, and a computing unit having a traveling element with a supporting carriage therefor, of means for connecting said supporting carriage to said typewriter carriage, such that said supporting carriage is retarded step by step by said typewriter carriage, said connecting means enabling the typewriter carriage to return said traveling element, and means for returning said supporting carriage, said connecting means being also arranged so that the typewriter carriage does not tend to return said traveling
25. 57. In a calculating machine, the combination with a typewriter carriage adapted for advancement, and a computing unit having a traveling element with a supporting carriage therefor, of connections from said typewriter carriage to said supporting carriage, enabling said typewriter carriage to control the advancement of said traveling element by obstructing the movement thereof, and a separate drive for said traveling element, enabling the same to keep pace step by step with the movement of said typewriter carriage as the obstructing action thereof is intermittently withdrawn.
30. 58. In a calculating machine, the combination with a typewriter carriage adapted for advancement, and a computing unit having a traveling element with a supporting carriage therefor, of connections from said typewriter carriage to said supporting carriage, enabling said typewriter carriage to control the advancement of said supporting carriage by obstructing the movement thereof, a separate drive enabling said supporting carriage to keep pace step by step with the movement of said typewriter carriage as the obstructing action thereof is intermittently withdrawn, and silencing means for said obstructing connections, enabling undisturbed return movements of said typewriter carriage.
35. 59. In a calculating machine, the combination with a typewriter carriage adapted for advancement, and a computing unit having a traveling element with a supporting carriage therefor, of a drive for said typewriter carriage, a separate drive for said supporting carriage, and a one-way connection between said carriages, enabling said typewriter carriage to control the movements of said supporting carriage solely in one direction.
40. In testimony whereof I have signed my name to this specification, in the presence of two subscribing witnesses, on this 22nd day of November, A. D. 1910.
- SAMUEL E. CARLIN.
